COMBINED ASH TRAY, LIGHTER AND DESK SET

Raymond Lee Smith, Lansing, Mich., assignor to Spot-litr, Inc., Lansing, Mich., a corporation of Michigan

Filed July 26, 1962, Ser. No. 71,061

Term of patent 14 years

(CL. D85—2)

FIGURE 1 is a side perspective view of a combined ash tray, lighter and desk set, showing my new design;

I claim:

The ornamental design for a combined ash tray, lighter and desk set, as shown.
